Nixon(57) **CLAIM**

The ornamental design for a dishwasher basket, as shown and described.

DESCRIPTION

FIG. 1 is a top front perspective view of a dishwasher basket showing my new design;

FIG. 2 is a front view thereof, with the rear view being a mirror image;

FIG. 3 is a right side view thereof, with the left side view being a mirror image;

FIG. 4 is a top view thereof;

FIG. 5 is a bottom view thereof; and,

FIG. 6 is a bottom rear perspective view.

The dashed broken lines in the figures show portions of the dishwasher basket that form no part of the claimed design.
